Jr. J. C. Faskewatty.

UNITED STATES PATENT OFFICE.

JAMES B. WILLIAMS, OF GLASTONBURY, CONNECTICUT.

WHIFFLETREE-HOOK.

SPECIFICATION forming part of Letters Patent No. 296,265, dated April 1, 1884.

Application filed August 8, 1883. (No model.)

To all whom it may concern:

Be it known that I, JAMES B. WILLIAMS, a citizen of the United States, residing at Glastonbury, in the county of Hartford and State of Connecticut, have invented certain new and useful Improvements in Whiffletree-Hooks; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to whiffletree-hooks or devices for fastening traces to whiffletrees; and it consists of a spindle that is fixed in each end of the whiffletree and carries a fixed button and a movable button, the contiguous faces of which are recessed, so that when the movable button is turned to a right angle with the fixed button said recessed buttons will interlock under the pressure of a spring that is carried on the spindle, as hereinafter more fully set forth.

In the annexed drawings, illustrating my invention, Figure 1 is a perspective view of my improved whiffletree-hook. Fig. 2 is a sectional view of the same, the buttons being aligned for the passage of the cockeye or opening in the end of the trace. Fig. 3 is an end view of the device as shown in Fig. 2. Fig. 4 shows the movable button turned at a right angle to the fixed button and locked therewith. Fig. 5 illustrates a modification in the position of the locking-spring. Fig. 6 represents a modified form of spindle. Fig. 7 is a section on the line $x-x$ of Fig. 6. Fig. 8 is a perspective of one of the buttons. Fig. 9 is a top view of whiffletree with a cap on its end, and Fig. 10 is an end view of said cap.

Like letters of reference are used to designate like parts in the several views.

In each end of the whiffletree A is screwed or driven a spindle, B, that carries a disk or 45 washer, C, which abuts against the end of the enlarged shouldered portion or body of the spindle, as shown in Figs. 2, 4, and 5, this enlarged portion of the spindle being flush with the end of the whiffletree, against which the 50 washer C also abuts, as shown in Fig. 2. The projecting portion of the spindle carries a fixed button, D, which is preferably oblong or ellip-

tical in shape, as shown in Figs. 3 and 8. The spindle also carries a movable button, E, which corresponds to the fixed button in form and size. 55 These buttons are arranged in contact with each other, and their contiguous faces are recessed at a , as shown in Figs. 2, 4, and 8, so that the buttons may be locked together when turned at right angles. That portion, b , of the 60 spindle B which is between the washer C and the fixed button D forms a bearing for the trace F, which is shown in dotted lines in Fig. 1. It will be seen that when the buttons D and E are aligned, as shown in Figs. 2 and 3, the cock-eye or opening in the end of the trace can be 65 passed over the buttons and onto the spindle, where it is secured by turning the movable button E, so that its recess a will engage with the recess in the face of the fixed button, the movable button being held in this position at a right angle to the fixed button D by the pressure of a spring, G, that is arranged on the spindle. By drawing the button E slightly away from 70 the fixed button D, the former may be readily turned into alignment with the latter, so as to 75 enable the trace to be detached. It will be observed that the ends of the recesses a formed in the contiguous faces of the buttons, are beveled, so as to facilitate the engagement and dis- 80 engagement of the parts.

The spring G, which is arranged beyond or to the outer side of the trace-bearing b , may be of any desired form, a flat or semi-elliptic spring, however, being deemed preferable. This spring 85 may be placed either on the end of the spindle, as shown in Figs. 1, 2, 4, or it may be arranged between the buttons D and E, as shown in Fig. 5. When a flat or semi-elliptic spring is used, the ends of the button E are provided 90 with lugs or bearings $c-c$ for the ends of such spring, as shown in Figs. 1, 2, and 5, a central bearing for the spring being afforded either within the recessed portion of the button D, when the spring is placed between the buttons, 95 or by means of a small washer, d , on the end of the spindle, when the spring is arranged on the outer side of the movable button. This washer may be held upon the spindle by any suitable means.

It is obvious that the lugs $c-c$, that are formed on the ends of the button to afford a bearing for the ends of the spring G, can be extended, if desired, around the edge of the button, so as

to form a flange to protect the spring, as well as keep it in position.

The trace-bearing *b*, or that portion of the spindle between the washer *C* and the fixed button, may be of a cylindrical or other suitable form, the non-circular or partly-elliptical form shown in Figs. 6 and 7, however, being preferable, as affording a firm bearing for a wrench in turning the spindle into the end of the whiffletree, while at the same time it presents no sharp corners that would be liable to cut the trace. This construction also forms a shoulder that can be used in driving the spindle into the whiffletree without battering the end of the spindle.

If desired, the disk or washer *C* may be made in one piece with the band *e*, that is applied to the end of the whiffletree, thus forming a cap or ferrule, *C'*, Figs. 9 and 10, through which the spindle passes. This construction is especially intended to be used in connection with the non-circular form of trace-bearing shown in Figs. 6 and 7, an elongated partly-elliptical opening, *f*, being formed in the end of the cap or washer, as shown in Fig. 10, which opening corresponds in form with said trace-bearing, one end of which fits in the opening *f*, so that all liability of twisting or turning the parts is obviated. This cap or ferrule *C'* is provided with wings or straps *g g*, that may be secured to the whiffletree by means of screws or rivets, as shown in Fig. 9.

Having thus described my invention, what I claim as new, and desire to secure by Letters Patent, is—

35

1. A whiffletree-hook having, in combination outside of its trace-bearing, a stationary and a movable recessed button and a flat spring to keep the buttons in contact, one of said buttons having a flange or lug at each end or around its edge, for the purpose of keeping in position and protecting the spring, substantially as shown and described.

2. In a whiffletree-hook, a flat spring rotating on its center, in combination with a recessed or flanged button, substantially as shown and described.

45

3. The combination, with the whiffletree *A*, provided with a spindle, *B*, having a partly-elliptical trace-bearing, *b*, and a recessed button, *D*, fixed to the spindle at the outer end of said bearing, of the movable recessed button *E*, having lugs or bearings *c c*, the spring *G*, arranged on the spindle at the outer side of the trace-bearing, and the cap *C'*, having wings *g g* and provided with an end opening corresponding with the form of the trace-bearing, substantially as described.

50

In testimony whereof I affix my signature in presence of two witnesses.

JAMES B. WILLIAMS.
